TELEPHONE SYSTEM

George Hecht, Astoria, N. Y., assignor to Bell Telephone Laboratories, Incorporated, New York, N. Y., a corporation of New York

Application October 23, 1940, Serial No. 362,345

4 Claims. (Cl. 179—18)

This invention relates to telephone systems and particularly to the receiving equipment of a transmission line over which alternating currents, preferably within the voice frequency range, are transmitted for effecting the operation of said equipment to control, in turn, the selective positioning of switching apparatus. More particularly, the invention is in the nature of an improvement in the receiving equipment of the telephone transmission line disclosed in Patent 2,269,022 issued to G. Hecht and A. A. Lundstrom on Jan. 6, 1942. In said patent is disclosed a telephone system of the type in which automatic switches are controlled by means responsive to alternating currents of different frequencies generated at a subscriber's station and transmitted over a line terminating in a plurality of channel detectors each selectively tuned to a different one of the signal frequencies and responsive thereto to operate a relay which, in combination with a relay operated over another channel detector responsive to a current of another signal frequency, serves to function a settable register, or sender, in which is locked-in a record of the digit indicated by the two operated relays; that is, by the two frequencies transmitted from the subscriber's station.

In systems of this kind where the signal generating instrument is, usually a device comprising a plurality of keys or the like which are operated to produce the different combination of frequencies to which the channel detectors are respectively tuned to respond, it very often happens that, in depressing a digit key, two or more of them are accidentally depressed together, in which event the amount of signal energy produced may be greater than that available by the depression of a single key (since only a small fraction of the physical energy expended in depressing a key is utilized for conversion into equivalent electrical energy) and the number of frequencies generated will be four or more instead of two, thus endangering the channel detectors to operate falsely. However, the telephone transmission line disclosed in the above-mentioned patent to Hecht and Lundstrom employs a volume limiting device which provides a ceiling for the maximum energy which may enter the channels. Since, in this case, the energy applied to the volume limiting device is carried by four or more frequencies, the output energy for application to the channels will be the same but will be carried by four or more frequencies instead of two. Under ordinary signaling conditions, the quantity of output

energy provided by the ceiling of the volume limiter will be sufficient to operate two of the channels if said energy is carried by two of the frequencies to one of which each of the two channels is tuned to respond. But when the same amount of energy is carried by more than two frequencies, the energy is divided between more than two channels and that available for each of the channels may not be sufficient to operate them, in which event no digit is recorded and the sender will function as though the subscriber had omitted to transmit one of the digits of the wanted number.

In accordance with a feature of this invention, whenever the subscriber depresses two or more keys simultaneously and, as a result, the channels will not operate for the reasons above stated, means are provided whereby the sender is signaled to cancel whatever digits have already been registered therein and to transmit "re-order" tone back to the subscriber who will understand from this tone that he is to restore his telephone instrument, listen for "key tone" and thereafter depress the generating device keys all over again for the retransmission over the line of the complete number of the wanted subscriber.

This and other features of the invention will be more readily ascertained from the following detailed description of said invention, appended claims and attached drawing in which is shown schematically certain elements of the telephone system more completely disclosed in Patent 2,237,742 issued to A. A. Lundstrom on April 8, 1941, and in which certain other elements to which my invention more directly relates, are shown in detail.

Referring, now, to the drawing, A represents a subscriber's station in an automatic telephone system, said station being equipped with a device 1 suitably arranged to produce one or more currents of different frequencies in the voice frequency range in response to the depression of keys or the like that represent digits or other characters making up the wanted designation, 2 represents a line extending from the station instrument to the central office whence, through one of a plurality of selectable sender connectors 13, the line is extended to an idle sender which comprises coupling transformers 3, 4, 5, 6 and 7, amplifiers 8 and 9, volume limiter 11, the enabler circuit 10, relays 31 and 32 which function from the enabler to signal the sender to transmit recorder tone according to the principles of the present invention, and the channel de-

tectors f_1, f_2, f_3, f_4 and f_5 individually so designated in accordance with the frequency to which each of the channels is respectively assumed adapted to respond, which channels include individually responding relays and the settable register relays which follow the operation of the channel relays when operated to signalize an incoming impulse. The amplifiers 8 and 9 and the volume limiter 11 are commercially available circuit units while the channel f_1-f_5 are completely disclosed in the above mentioned patent to A. A. Lundstrom, and to which reference is made for a more complete understanding thereof although it is to be understood that the invention is not limited to channels of this description.

In the operation of the invention, a call is initiated at station A by the removal of the station instrument from the switchhook whereupon the line is then extended by any suitable means to the central office at which an available sender is then connected to said line through the medium of a sender connector 13 after which "key tone" is transmitted back to the calling station A, by circuits not shown, as a signal that the sending device 1 may be operated to transmit the number of the wanted station, all in the manner described in the above-mentioned patent to A. A. Lundstrom.

When any one of the ten keys of the sending device 1 is operated, two out of the five defined frequencies f_1-f_5 are produced in the combination required to designate the digit represented by the key depressed and the resulting current produced is transmitted over a circuit which may be traced from one side of the sending device 1, over the lower conductor of the looped pair 2, lower back contact of relay 12, next to the inner contacts of sender connector cut-in relay 13, primary winding of transformer 3, inner contacts of relay 13, top outer back contact of relay 12, upper conductor of looped pair 2 to the other side of the station sending device 1. The current composed of the two frequencies is induced in the secondary winding of transformer 3 and fed into the input side of amplifier 8 whence, after suitable amplification, it is applied from the output side to the input sides of transformers 4 and 5, respectively, whence through the transformer coupling it is further applied, through transformer 4, to the input side of the volume limiter 11 and, through transformer 5, to the input side of amplifier 9.

Considering that portion of the signal energy which passes into the volume limiter 11, the energy causes the volume limiter to operate and regulate the energy output in accordance with its adjustment which may be such as to limit the magnitude of output to that required for the satisfactory operation of the channel detectors and no more, regardless of the magnitude of the input energy. The reason for doing this is, of course, to prevent overloading any of the channel detectors which, should it occur in the event of a heavy input signal due, say, to a very short loop 2, would cause false operation of adjoining channel detectors by currents present in the frequency spectrum generated thereby and thus cause the registration of a false number. Hence by adjusting the volume limiter to a suitable ceiling of output energy above the operate level of the channel detectors, their false operation upon heavy signal currents is avoided.

The energy output from the volume limiter 11 is applied, through transformer 7, to the variable

resistance pad 14 whence it is applied through suitable filters BPF to the grids of the detector tubes in each of the channels f_1-f_5 . Since these tubes are normally inactive, the channels that would be involved by the two frequency components in the current transmitted through variable resistance pad 14, do not operate.

Considering, now, that portion of the signal energy which is transmitted to the enabler circuit 10 via transformer 6, it will be observed that said enabler comprises a rectifier bridge 16 and four polarized relays 17, 18, 19 and 20, each having a permanently closed polarizing circuit through its lower winding which causes the armature thereof to assume the position indicated in the drawing. Further, between each two relays, beginning with relay 17 and ending with relay 31, there is an intermediate condenser-resistance network which joins a contact of the relay on the left with the upper winding of the relay to the right. Considering relays 17 and 18, for instance, the network made up of resistance 23 and condenser 21 joins the right contact of relay 17 with the upper winding of relay 18. Since the armature of relay 17 is connected to positive battery 30, condenser 21 is normally charged to the potential of this battery. Condenser 24 of the network between relays 18 and 19 on the other hand, is normally at ground potential since it has ground applied to it through the left contact of relay 18. Contrariwise, condenser 29 of the network between relays 19 and 20 is charged to the potential of the battery 30 through the upper winding of relay 20 and resistance 28 since the short-circuiting ground path for condenser 29 is normally open at the right contact of relay 18, which fact leaves condenser 29 exposed to the charging circuit that traces from the positive pole of battery 30, through the upper winding of relay 20, resistance 28 and condenser 29 to ground. Similarly, condenser 33 is normally discharged by the connection of ground to its top terminal via the left contacts of relay 20, said ground also completing a normal circuit through the top winding of relay 31 and resistance 34 to battery. The current flowing through this winding counterbalances the effect of the current flowing through the always closed biasing circuit through the middle winding of said relay, thereby causing the armature thereof to be disengaged from its right contact as shown in the drawing.

Assuming, therefore, that relays 17, 18, 19, 20 and 31 have their respective armatures in the positions shown, and that condensers 21, 24, 29 and 33 are charged, discharged, charged and discharged, respectively, as indicated above, ground is normally disconnected from conductor 15 at the right contact of relay 20, which conductor is, in turn, connected to the cathodes of the detector tubes of the several channel detectors f_1-f_5 , and causes them to be normally unresponsive to signal energy incoming over the resistance pad 14.

Now when a portion of the incoming energy is applied to the rectifier bridge 16, said energy is rectified and the current thereof is applied to the upper winding of relay 17. The combined effect of the current now flowing through the upper winding of this relay and that always flowing through its lower winding is such as to cause its armature to swing from the right contact into engagement with its left contact. Since condenser 21 is normally charged to the potential of

battery 30 over the armature and right contact of relay 17, the opening of these contacts immediately causes the condenser to discharge to ground through resistance 23 and the upper winding of relay 18 to prolong the flow of current normally flowing through this winding of said relay. The direction of the discharge current as well as the normal current through the upper winding of relay 18 opposes that of the current normally flowing through its lower winding, and since the discharge current is initially of greater intensity through the proper choice of the ohmic value of resistance 23, the release of relay 18 is delayed and the armature thereof is caused to break away from its left contact at a time subsequent to the operation of relay 17 and to engage its right contact.

During the time that the armature of relay 18 is engaged with its right contact, and remembering that condenser 24 is kept at ground potential while the armature of this relay is making with its left contact, then, as soon as the armature breaks with its left contact, condenser 24 immediately begins to charge over a circuit traced through resistance 26 and the upper winding of relay 19 to battery 30, to continue to maintain the normal current over this path for a short time subsequent to the operation of relay 18, whereupon the effect of the current through the lower winding of relay 19 continues to be neutralized for a short time by this charging current so that the armature of relay 19 is caused to break with its left contact at a time subsequent to the operation of relay 18, that is, at the time when the charging current for condenser 24 through the upper winding of relay 19 is no longer powerful enough to overcome that through the lower winding of the relay.

At the instant that the armature of relay 18 engages its right contact and before the armature of relay 19 leaves its left contact, a discharge path is completed for condenser 29 which may be traced from ground, through condenser 29, resistance 27, left contacts of relay 19 and right contacts of relay 18 to ground. The charge accumulated on condenser 29 as a result of the charging current in the circuit through the upper winding of relay 20 is quickly drained off through the low resistance 27 and a current flow is quickly established in the upper winding of relay 20 for its rapid operation whereby ground is connected to conductor 15 to sensitize the detectors so that, when the armature of relay 19 breaks with its left contact, condenser 29 is in an uncharged condition and immediately starts recharging through the upper winding of relay 20 to prolong the current flow therethrough for a subsequent period. This charging current overcomes the effect of that normally flowing through the lower winding of relay 20 and causes the armature thereof to engage its front contact, thus applying ground to conductor 15 which, as said before, is connected to the cathode of each of the detector tubes in the channel detectors f1—f5. The channel detectors are now made responsive and the two which are adapted to respond to the two frequencies in the input current that flows into their respective input side through resistance pad 14 operate, causing, in turn, the operation of their respective anode relays which, in their turn, cause the operation of relays in the register to designate the digit or character marked by the two frequencies.

It is to be noted that relay 18 will make its right contact at a time subsequent to the ener-

gizing of relay 17 by rectified current flowing through the rectifier bridge 16. This time is, of course, determined by the discharge time of the condenser 21 through resistance 23 which causes 5 the normal current through relay 18 to endure for a time (let us say, for example, 20 milliseconds) after the operation of relay 17. At this time relay 18 releases and closes its right contact whereby condenser 29 is quickly discharged 10 through the low resistance 27 and establishes a current through the upper winding of relay 20 to cause its immediate operation. This, as explained, places ground on conductor 15 to sensitize the detectors at a time 20 milliseconds after 15 the signal was first applied. This delay is for the purpose of allowing the unwanted spectrum energy in adjoining channels to dissipate itself to avoid unwanted channel operation from this source. It is the purpose of the condenser 24 to 20 maintain by its discharge current through the upper winding of relay 19, the normal current flowing therethrough to hold relay 19 operated on its left contact for a time sufficient to permit the complete discharge of condenser 29 through resistance 21, from contacts of relay 19 and right 25 contacts of relay 18 to ground. Relay 19 then operates to break its left contact and thereafter relay 20 is maintained on the charging current from battery 30, top winding of relay 20, resistance 28, to condenser 29. When this discharge current has dissipated itself, relay 20 will operate and break its back contact to remove ground from lead 15 regardless of how long thereafter that energy is delivered to relay 17 by the signal. 30 The length of time during which the armature of relay 20 engages its right contact to cause the channel detectors to remain activated depends, of course, upon the constants of condensers 24 and 29 and resistances 26 and 28 which 35 may be chosen to provide any interval desired. However, when the condenser 29 is completely charged, the current through the lower winding of relay 20 again becomes effective, the armature of the relay breaks away from its right contact and 40 ground is removed from conductor 15 and, therefore, from the cathodes of the detector element of the several detector channels which, in consequence, will no longer respond to any signal energy forthcoming over resistance pad 14 and 45 50 thereby cause their associated anode relays to release.

The circuit conditions prevailing in the enabler during the presence of signal energy in bridge 16 and after the armature of relay 20 has again 55 made its left contact, is that relay 17 will have its armature making with its left contact, relay 18 will have its armature making with its left contact, while relay 19 will have its armature on its left contact which will in no way affect the charge on condenser 29 or the condition of the armature of relay 20 which is out of engagement with its back contact. Hence it makes no difference how long signal energy prevails upon the line subsequent to the armature of relay 20 breaking away from its right contact, said energy will be ineffective to operate the channel detectors inasmuch as ground is disconnected from the cathodes of their several detector elements.

When relay 20 breaks its left contact to engage 70 its right contact for the purpose of applying ground to conductor 15 in order to sensitize the detectors, the short circuit for condenser 33 is removed and a charging circuit for this condenser is immediately effective over resistance 34, 75 top winding of relay 31 to battery. This charg-

ing current has the same effect, for an interval of time, upon relay 31 as the current previously flowing through its upper winding directly from ground over the left contact of relay 20, which is to say, that until the charging current decays to the point where it no longer is powerful enough to oppose the effect of the current flowing through the middle winding, the armature of relay 31 remains disengaged from its right contact. The time interval is, of course, determined by the capacity of condenser 33 and the value of resistance 34 and both should be of such value as to delay the pulling power of the current through the middle winding of relay 31 until sufficient time has been provided for the operation of any of the channel relays in consequence of the signal current activating the correlated channel detectors after ground is applied to conductor 15. Under these circumstances the two channel detector relays, when operated, will close a circuit through the lower winding of relay 31 over a path which may be traced, for instance, from battery through the lower winding of said relay, resistances 25 and 22, over the inner contacts, respectively, of channel relay of detector channel f2 and detector channel f1 to ground. The current that flows through the lower winding of relay 31 is in the same direction as that which flows through the top winding under normal conditions, and when condenser 33 is being charged it opposes the effects of the current flowing through the middle winding of said relay so that if, when the charging current has decayed, the channel relays have operated and the circuit through the lower winding of relay 31 has been established, the current flowing therethrough will oppose that flowing through the middle winding of said relay and the same will remain in its normal position; that is to say, with its armature disengaged from its right contact.

It may now be supposed that the subscriber, in the course of keying up the desired number upon generating device 1, accidentally depresses two keys instead of the one designating the digit to be transmitted. In this case the quantity of alternating current generated will be more and will be carried by at least three of the signal frequencies. Since the gain of the volume limiter 11 is set so that the output is never more than maximum permitted by the gain adjustment, the signal energy that seeks entry into detectors f1—f5 will be divided between the three or more channels involved. The portion of the energy thus received by each channel is not enough to cause the operation of its corresponding channel relay so that no channel relay will operate under the condition assumed. However, since by the time two of the channel relays are supposed to operate the charging current for condenser 33 will have decayed to the level at which it is powerless to oppose any longer the current flowing through the middle winding of relay 31, relay 31 will operate on the current through said middle winding unless the operation can be prevented by the closure of the circuit through the lower winding at one or more of the operated channel relays as before described. But since the channel relays cannot operate because of the insufficient signal energy, the circuit through the lower winding is not closed whereupon relay 31 operates and closes an obvious circuit for relay 32 which, upon operating, locks through a set of contacts to off-normal ground. This relay may be used to establish signaling circuits through its contacts to appropriate parts of the sender for

signaling the sender to transmit "re-order" tone to the calling station A and to cancel whatever digits have already been registered in the sender. Since the manner and means by which such circuits are established form no part of the present invention, the same is not shown although by reference to the sender disclosed in the above-mentioned patent to A. A. Lundstrom, it will be evident to anyone skilled in the art that the arrangement and disposition of such circuits are relatively simple matters.

When the signal impulse is terminated (assuming the correct depression of a key at device 1), relay 17 will restore to its normal condition, re-establishing quickly the charging circuit of condenser 21 and the circuit through the top winding of relay 18 to cause it to make its left contact. Relay 18 operates and causes the quick establishment of the circuit through the top winding of relay 19 to cause it to quickly make its left contact. In this operation, condenser 29 has not been charged since ground via the contacts of relays 18 and 19 has not been removed. The release of the channel relays will open the circuit through the lower winding of relay 31, but, since by this time the armature of relay 20 is already on the left contact, the circuit through the top winding of relay 31 is reestablished to oppose that through its middle winding and thus keep relay 31 normal. The enabler circuit is now ready for another cycle of identical operations upon the reception of the next impulse.

While I have described my invention and the means for utilizing the same in connection with its specific application to a particular kind of a transmission line, it is to be understood that various other applications and embodiments thereof may be made by those skilled in the art without departing from the spirit of the invention as defined within the scope of the appended claims.

What is claimed is:

1. A register sender of a telephone system comprising a plurality of detector channels each adapted to respond to signal energy within a definite frequency band, means responsive to incoming signal energy for activating said detector channels to respond to said energy, and means operative in the event that the available signal energy is not sufficient to operate said detector channels subsequent to their activation.

2. In a telephone system, the combination with a telephone station and means located thereat to produce signal frequencies combined in predetermined invariable numbers, of a sender connected to said line comprising a plurality of channel detectors each adapted for response to a specific signal frequency of a combination generated at said station, means for limiting the input signal energy for said channel detectors to an amount sufficient to operate as many channels simultaneously as there are signal frequencies in the invariable number in the combination of frequencies transmitted from said station, and means operative in the event that said signal energy is carried by more than said invariable number of signal frequencies and the energy carried by each of the single frequencies is not sufficient to operate the associated channel.

3. In a telephone system the combination with a transmission line comprising a plurality of channel detectors each adapted for response to a specific frequency of a plurality of frequencies present in a signal current transmitted over said line but normally unresponsive thereto, means

responsive to said signal current for activating said channel detectors for response to their respective frequencies in said signal current, and means for maintaining said channel detectors activated for a predetermined interval, said means including other means which are operative in the event that none of said channels respond to said signal current subsequent to activation.

4. In a telephone system, a transmission line terminating in a plurality of channel detectors each adapted for response to a specific frequency in a plurality of frequencies present in a signal current transmitted over said line, and means responsive to said signal current for activating said channel detectors for response to their respective frequencies and for registering the fail-

ure of any of said channels to respond to said signal current, said means comprising a rectifier coupled to said line, a plurality of relays cascaded from said rectifier of which the first is responsive to said signal current after rectification by said rectifier, the last of which operates to denote failure of any of the channel detectors to operate, the next to the last of which applies activating potential to said channel detectors for a predetermined interval, and impedance networks intermediate each pair of said plurality of relays except the first and last for controlling their operate time to make up said predetermined interval including the time required to operate said last relay in the event that none of the channels operate on said signal current.

GEORGE HECHT.
